SUCTION CLEANER OR THE LIKE

Roger H. Ramsey, Akron, Ohio, assignor to The Hoover Company, North Canton, Ohio

Filed Dec. 4, 1972, Ser. No. 311,860

Term of patent 14 years

Int. Cl. D15—05

U.S. Cl. D6—166

FIG. 4

FIG. 5

FIG. 6

FIG. 1 is a perspective view from the rear of a suction cleaner embodying my new design;

FIG. 2 is a rear elevation thereof;

FIG. 3 is a front elevation thereof;

FIG. 4 is a top plan view thereof;

FIG. 5 is an elevational side view thereof, and

FIG. 6 is a perspective view taken from the front thereof.

The broken line disclosure in FIGS. 1 and 6 is for illustrative purposes only and forms no part of the claimed design.

I claim:

The ornamental design for a suction cleaner or the like, as shown and described.
